(54) **CLAY, POTTERS', PURIFYING**

(76) Inventor: **Adam Weber**

Adam Miller, Banker Co., Pennsylvania

Letters Patent

The Schedule referred to in these Letters Patent and making part of the same containing a description in the words of the said Adam Miller himself of his improvement in a machine for purifying Potter's Clay.

To all to whom these presents shall come. Be it known that Adam Miller of the Borough of Monaca, in the County of Beaver & State of Pennsylvania have invented a novel and very useful apparatus or machine for the purpose of purifying Potter's Clay, never before known by the use of which the clay becomes more pure and free from of the time sand - The following is a full and exact description of the construction & operation of the said apparatus or machine as invented by me. A is a side view of the bench. B is a cylinder which may be made of wood, Copper Brass or otherwise. C is name the presser, the upright C has the central part of the wood cut out so as to permit the lever D. work up and down in it. The lever D works on a pin E. The presser C works on a pin F. in both sides of the lever D. It is a treadle fastened on the lever D. by a wire extended up to it as seen in the drawing accompanying this specification. It is a sieve connected with the cylinder B to rest on it. The machinery may be made of any size the same result will be obtained if all the parts are made to correspond. The mode of operation is as follows. The Potter's clay being measured is then put into the cylinder B it sinks and rests on the sieve attached to the bottom of the cylinder. The lever D is then raised which necessarily raises along with it the presser C. The presser C is then directed into the cylinder B. it works on the clay at the bottom, the workman then puts his foot into the treadle F. and his hand on the lever D. towards the end. he then lets his weight on the lever D. which forces the clay through the sieve through the hole below the sieve in the bench and causes the clay to be purified at the same time. - When the sieve becomes fully filled with sand, pottery stones &c all that is impure for the

workman is to apply water to the bottom of the potter's wheel before he drops it into the cylinder for the purpose of throwing clay through the sieve. This done when he raises the proper by means of the lever D it will bring along on its bottom all impurities. It must here be remarked that there is a machine which is somewhat similar to my invention above described, used for the purpose of making sausages and for no other, and could by no means be used for the purpose for which I have invented my above described machine as construction and operation is entirely different. I claim only the invention of the above described machine. I do not intend to limit myself to the precise modes and forms &c by me set forth but modify amongst them as I may deem proper whilst the same results are attained by analogous means, and the same general principles &c are retained.

Test.
